GLOVE TURNING MACHINE

Louis Brownstein, Brooklyn, N. Y., assignor to
Isidor Gerber, Brooklyn, N. Y.

Application April 24, 1940, Serial No. 331,310

28 Claims. (Cl. 223—40)

This invention relates to automatic glove turning machines of the type disclosed in my co-pending application for patent for Combined glove turning and pressing machines, Serial No. 267,553, filed April 13, 1939, to which reference is hereby made.

The present invention pertains to improvements in the turning mechanism whereby said mechanism is substantially simplified and rendered positively acting and efficient, and correct mounting of the glove in right-side-out position on a heating form is assured, it being intended that the glove be later stripped from the form and pressed. Since only part of the glove pressing mechanism is shown herein, reference is hereby made to my application for patent for Glove pressing machine, Serial No. 263,125, filed March 21, 1939, now Patent No. 2,199,778, dated May 7, 1940, for a full disclosure of the heating, stripping and pressing mechanism.

Before a glove can be mounted automatically on the heating form of the pressing mechanism, it must first be turned from an inside-out position to a right-side-out position since the glove parts are stitched together in an inside-out position. My said co-pending application, Serial No. 267,553, discloses means for accomplishing this operation automatically after the glove is manually mounted by the operator on a turning form. Thereafter, the glove is automatically turned and mounted in right-side-out position on a heating form then stripped from the form and pressed.

Difficulty has been experienced in turning the glove thumb, it being understood that the machine should operate on the glove regardless of whether it is a left hand or a right hand glove. Full control of the thumb during the turning operation is therefore one of the important features of the present invention.

This invention further contemplates the simplification and the improvement of the efficiency of the glove turning means, whereby the glove is properly mounted on a heating form despite inaccuracies in the stitching of the glove during its manufacture or the resistance of the different types of material from which the glove may be made; the use of positively actuated grippers for accomplishing the greater part of the turning of the glove and the mounting thereof on the heating form, and the provision of an improved thumb holding device whereby correct turning of the thumb cannot fail to take place when the remainder of the glove is turned.

The various objects of the invention will be

clear from the description which follows and from the drawings, in which,

Fig. 1 is a front elevation of a glove turning machine embodying my invention, certain of the operating parts, however, having been omitted and the glove grippers being shown at the right hand part of the machine for the sake of clarity.

Fig. 2 is a side elevational view thereof, taken from the left end of Fig. 1, the tucker blades for the thumb and the grippers for the wrist or open end of the glove having been omitted.

Fig. 3 is a front elevational view of the operating mechanism for the thumb tucker blades.

Fig. 4 is a fragmentary top plan view of the turning form and of the glove grippers showing in dash-dot lines an intermediate position of the grippers during the glove turning operation.

Fig. 5 is a fragmentary top plan view of the gripper showing other positions assumed by the grippers during the turning operation.

Fig. 6 is a vertical section taken on the line 6—6 of Fig. 4 showing the grippers in more detail.

Fig. 7 is a fragmentary enlarged top plan view and section of the thumb holding means for insuring correct turning of the glove.

Fig. 8 is a fragmentary sectional view of one of the fingers of the turning form and of part of the co-operating or heating form, showing the rods whereby the turning of the glove is initiated.

Fig. 9 is a fragmentary front elevation and vertical section of the glove turning form and of the upper one of the grippers in the initial position thereof at the beginning of its stroke and just before it is operated to grip the wrist end of the glove.

Fig. 10 is a top plan view of the draw-on blades and of the operating mechanism therefor.

In the practical embodiment of the invention which I have shown by way of example, the heating forms 10 are of the electrically heated type, each provided with an electrically operated heating element and with four fingers adapted to receive the fingers of the turned glove. The forms 10 are mounted on the shaft 11 which is intermittently operated by a suitable Geneva movement in the direction of the right hand arrow of Fig. 1 or in a clockwise direction to align one of the heating forms 10 end for end with one of the turning forms 12. Current is supplied to the heating element of the heating form by suitable connections to the commutator 13 at the end of the shaft 11. Means are also provided for operating the tucker rods 14 through

the fingers of the form 10 all in a manner and by means clearly shown and described in my prior Patent No. 2,199,778 and my said co-pending application Serial No. 267,553, for the double purpose of initiating and turning of the gloves, and later for initiating the stripping of the glove from the heating form. No further description of the forms 10 or of the rods 14 or of the operating mechanism therefor is therefore deemed necessary.

Each of the various turning forms 12 extends radially from the common shaft 15 therefore, and are intermittently rotated by the Geneva mechanism 16, 17 (Fig. 2) on the shafts 15 and 18 respectively to carry the turning forms in succession into horizontal position and into alignment with a corresponding heating form 10 from which the glove has previously been stripped. The shaft 18 is rotated through the bevel gear 19 meshing with the bevel gear 20 on a motor shaft operated by a suitable motor, not shown. When the shaft 18 rotates, the Geneva part 17 is rotated and actuates the Geneva part 16 intermittently to rotate the shaft 15 and to carry each of the turning forms 12 successively into a horizontal rest position as shown in Fig. 1. The timing of the shafts 11 and 15 is such that the turning forms and heating forms are operated in unison with each other and about parallel spaced axes so that when the turning forms 12 are at rest, the heating forms 10 are also at rest. Consequently, one of the turning forms will be in coaxial and coplanar alignment with and adjacent to one of the heating forms during each rest period.

As best seen in Figs. 1 and 2, each of the turning forms 12 consists of an outer or index-finger tube 21, a second outer or small-finger tube 22 slightly shorter than the tube 21 and a pair of intermediate finger tubes 23 and 24 extending somewhat beyond the corresponding ends of the tubes 21 and 22. The intermediate finger tubes are supported by the plate 25 which is in turn supported by the finger tubes 21 and 22 or in any other suitable manner. The outer tubes 21 and 22 extend inwardly toward the shaft 15 past the plate 25 and are secured at their inner extremities to a plate 26 provided with a suitable hub 27 by means of which the plate 26 and the form fingers or tubes carried thereby are mounted in the proper position on the radial shaft 28 extending from the shaft 15. Each of the outer finger tubes 21 and 22 is open for that part of its length nearest the plate 26 as at 29 (Fig. 9) to impart a U-shaped cross-section to the inner end portions of said finger tubes as best seen in Figs. 6 and 9 and for the purpose later to be described.

Each of the finger tubes 21, 22, 23 and 24 is slightly flared or of larger diameter at its outermost end than at the remainder thereof to resist movement of the glove fingers off the turning form while the turning operation on the body portion of the glove is being performed.

Associated with the finger tubes and comprising part of each of the forms 12 is a pair of identical and opposed thumb holding members 30 and 31 of peculiar construction. One of said members as 30 is intended to enter into the thumb of a right hand glove and is arranged on one side of the index-finger tube 21 and the other as 31 is intended to enter the thumb of a left hand glove and is arranged on the other side of the index-finger tube. Each of said thumb holding members comprises the base 75

32 which is suitably secured to and projects substantially perpendicularly from the plate 26 and which terminates in a reduced portion 33 interposed between the pair of similar spring plates 34 and 35 arranged in face to face relation. Said plates are separated by the part 33 at their inner ends and adjacent their outer ends are in spring pressed contact at the substantially straight portions 36 thereof, the extreme ends 10 37 however being bent away from each other or bevelled to provide a triangular space for the easy entrance therebetween of a suitable tucker blade. Inwardly of the contacting portions 36 are the outwardly convex portions 38 providing a suitable space 39 between the spring plates to receive the inwardly tucked end part of the glove thumb at the proper time. The plates 34 and 35 being resilient, they are readily spread apart by a tucker blade pressed between them 15 past the ends 37 thereof. When, as shown in Fig. 7, the tucker blade 40 tucks the tip of the glove thumb between the plates as when the turning operation is commenced, and after the tucker blade is withdrawn said plates automatically close upon the end of the thumb and hold said end properly in place during the time that the turning of the remainder of the glove is being performed.

It will be understood that the tucker blade 30 may tuck a sufficient portion of the thumb end in between the thumb holding plates 34, 35 to reach the space 39, in which case the parts 36 of the plates engage and grip a substantial area of the partly turned thumb of the glove just 35 beyond the tip of the thumb. While I have hereinbefore referred to only one of the tucker blades 40, it will be understood that a pair of such blades is provided, one for each of the thumb members 30 and 31. The blades 40 are 40 each pivotally mounted as at 42 on an arm 41 (Figs. 1 and 3). The arms are oscillated in unison at the proper time to cause one of the blades to enter between the plates 34 and 35 of the thumb member 30 and to cause the other 45 blade to enter simultaneously between the similar spring plates of the other thumb member 31. Consequently, the thumb of the glove is tucked in and partly turned regardless of whether a right hand or a left hand glove is mounted on the turning form 12.

The arms 41 are mounted on the tucker shaft 43 in the same spaced relation as are the thumb members 30 and 31. Said shaft 43 carries the crank 44. A connecting rod 45 connects one end 55 of the crank 44 to an end 46 of the arm 47 of the bell crank lever 48, which lever is loosely mounted on the shaft 15. A roller 49 on the arm 47 engages the cam 50 on the shaft 18 while a second cam roller 51 on the arm 52 of the bell 60 crank lever engages the smaller cam 53 on said shaft 18. Consequently, during the continuous rotation of the drive shaft 18, the cam 50 oscillates the lever 48 against the action of the spring 54 to reciprocate the rod 45, and to oscillate the crank 44, the shaft 43 and the arms 41 and thereby to oscillate the blades 40 in unison and to alternately insert them between and retract them from the spring plates of the respective thumb members 30 and 31 at the proper time. 70 Should the action of the spring 54 be insufficient to withdraw the tucker blade from between the spring plates after the cam 50 has left the roller 49, the cam 53 by its engagement with the roller 51 of the arm 52 aids the spring to withdraw the tucker blades.

Each of said blades enters between the spring plates and moves thereinto along a substantially straight line path by reason of its pivotal mounting on the arm 41 and the resistance offered by the spring plates. To maintain the tucker blade in its proper position for tucking, a stop pin 55 is provided on the arm 41 on one side of the pivot 42 and a second pin stop 56 on the other side of said pivot, said pins limiting the movement which the tucker blade may have about the pivot. The tucker blades 40 operate to initiate the turning of the thumb of the glove at about the same time that the tucker rods 14 of the heating form 10 operate to tuck the finger of the glove into the finger tubes 21, 22, 23, 24, it being understood that the tucking of the finger tips and thumb tip of the glove is accomplished while the forms 12 and 10 are in horizontal alignment and at rest.

Means are provided for thereafter turning the body of the glove, for also removing it from the form 12 and for mounting it on the form 10 while said forms are still at rest. Said means comprises a pair of traveling grippers one of which as 57 is arranged to operate during part of its movement in the open end of the finger tube 21 which becomes arranged at the top edge of the form 12 when said form is horizontal, the other gripper 58 being arranged to operate during part of its movement in the open end of the finger tube 22 at the bottom edge of the form.

The upper gripper 57 is turned out of the way of the heating form 10 and the turning form 12, to permit the form 12 carrying a glove in inside-out position to be rotated in the direction of the arrow of Fig. 1 into the glove dismounting position thereof and to permit an empty form 10 to be rotated into its glove receiving position. Since the position of the lower gripper 58 during its movement is such that it clears the forms when said forms are rotated, means are provided on the upper gripper 57 only to turn it at the proper time to permit movement of the forms, while the gripper 58 need not be rotated. Both of the grippers, however, are simultaneously reciprocated horizontally and in unison longitudinally of the machine first in one direction and then in the opposite direction by a traveling chain, the chain 59 operating the gripper 57 while the chain 60 operates the gripper 58 through suitable connections thereto. As shown in Figs. 1 and 2, the chain 59 is driven by suitable sprocket wheels on the spaced shafts 61, 62 respectively, such shafts being journaled in the frame of the machine, the shaft 61 also carrying a sprocket wheel operated by the chain 63 which also engages a sprocket wheel on the shaft 64 (Fig. 2). Said shaft 64 also carries another sprocket wheel engaging the chain 65 which is driven by a suitable sprocket wheel on the shaft 18. Similarly, the chain 60 is driven through suitable sprocket wheels through the chain 66 meshing with a sprocket wheel on the shaft 64.

A bracket (Fig. 6) carries the gripper 57 and is connected to the chain 59 by the slide 68 and the link 69, one end of the link being connected to the slide, and the other end to the chain 59. Said slide is guided in its movement by suitable guides as 70 on the frame 11 on the machine. The bracket 67 therefore moves longitudinally of the machine throughout the length of the chain 59 alternately in opposite directions.

The upper gripper 57 comprises the jaw-operating rod 72 urged upwardly by the spring 73 and mounted for vertical movement in the outer 75

end part of the horizontal arm **74**. The movable gripper jaw **75** is provided at the lower end of the rod **72** and co-operates with the resilient jaw member **76**, preferably of rubber or the like fixed in the slot **71** of said arm **74**. (See also Fig. 9.) It will be understood that when the jaw **75** moves upwardly toward the jaw **76**, a glove is firmly gripped therebetween. Such upward movement of the rod is controlled and effected by means of the arm **78** pivoted at one end on the shaft **79** and at its other end pinned to the rod **72**. The shaft **79** also carries the cam arm **80** terminating in the cam roller **81** operated by the fixed cam **91**. The shaft **79** is carried by a suitable extension of the sleeve **82** which is mounted on the upright fixed post **83**. A spring arranged within the sleeve and around said post urges the sleeve and the arm **74** carried thereby to rotate in a counter-clockwise direction as viewed in Figs. 4 and 5 into a position wherein the flanged base **85** of the sleeve engages the adjustable stop screw **86** of the bracket **67**.

It will be noted that when the cam roller 81 rises, the shaft 79 is rotated in a clockwise direction as viewed in Fig. 6, consequently lowering the arm 78 and opening the jaws 75, 76. When the cam roller 81 is permitted to drop, the arms 80 and 78 rotate in a counterclockwise direction as viewed in Fig. 6 thereby raising the rod 72 under the action of the spring 73 and closing the jaws 75, 76.

A gripper member 58 similar to the gripper 57 is similarly provided with jaws 75 and 76 carried by a similar arm 78 mounted on the similar shaft 79 and also has a similar cam arm 80 terminating in a cam roller 81 operated by the fixed cam 87. The jaw 75 of the gripper 58 is also carried by a rod 72 surrounded by a similar spring 73. However, the shaft 79 is carried directly on the bracket 88 supported by the slide 89 which is connected to the chain 69 by the link 90. It will be noted that in gripper 58, the sleeve 82, post 83, and spring 84 are omitted and that the gripper has no turning action about a vertical axis but only has a jaw closing and opening movement.

For the purpose of clarity, the grippers 57 and 58 are shown in Fig. 1 at the right hand end of the machine but it is to be understood that when 50 a glove is mounted on the horizontal form 12 as shown and is to be mounted on an empty form 10, said grippers 57, 58 are not at the place indicated in Fig. 1 but are arranged at the opposite end of the machine as shown in Fig. 4 instead. 55 In the position of Fig. 4, as shown by the full lines indicating the gripper, the cam roller 81 is on the high part of the cam 91 and consequently the jaws 75, 76 are open. Similarly, the 60 cam roller 81 of the gripper 58 is on the high part of the cam 87 and the jaws of said gripper are also open. When the chains 59 and 60 now become effective to move the grippers toward the right, the jaws 16 of said grippers pass into and through the open ends of the finger tubes 21 and 65 22 respectively underneath and above the wrist part 92 (Fig. 9) of the glove so that said part of the glove enters between the jaws of the opposed grippers at the top and bottom edges of the form 12. As the grippers move toward 70 the right from the position of Fig. 4, stripping of the glove from the form 12 is begun by the rod 72 and the glove is slightly loosened from the form. The finger tips are then tucked by the rods 14 of the heating form into the interior of 75 the finger tubes 21-24 (Fig. 8) while at the

same time the tucker blades 40 are rapidly operated to tuck the tip of the thumb between the spring plates 34, 35 and then to recede out of the plates. As the movement of the grippers toward the right continues, the cam rollers 81 thereof move off the respective fixed cams 91 and 87 whereby the springs 73 of the grippers become operative to close the jaws on the open end edge part of the glove. Continued movement of the grippers toward the right carries the left end of the glove as viewed in Fig. 1 toward the right while the finger tips and thumb tip remain in the finger tubes and thumb holding member. When the wrist part 92 of the glove has been carried to the right of the finger tips, the glove is turned and mounting thereof on the form 10 by the grippers is begun. Continued movement of the grippers to the positions thereof shown in Fig. 1 at the right end of the machine completes the turning of the glove.

As the turning of the glove is completed, the roller 81 of the gripper 57 rides up on the fixed cam 93 thereby opening the jaws and releasing the glove. Similarly, the roller of the gripper 58 rides up on a similar fixed cam and opens the jaws of that gripper. In this manner, the grippers serve not only to turn the glove but also to remove it from the form 12 and to mount it on the form 10. It will be understood that during the turning operation the flared ends of the finger tubes serve to prevent the finger tips from moving off the finger tubes too rapidly, while the spring plates 34, 35 of the thumb member serves to grip the thumb tip of the glove and retain it under full control in the proper position to assure proper turning of the glove, the pull of the grippers on the wrist part 92 of the glove pulling the thumb tip out of the grip of said spring plates as the turning is completed.

As has been hereinbefore indicated, on the return movement of the grippers 57, 58, toward the left from the position thereof shown in Fig. 1, the upper gripper 57 is rotated out of the way of the intermittently rotatable forms 10 and 12 to permit the next successive forms to be brought into the glove turning positions thereof. For this purpose, an arm 94 in the shape of a narrow arcuate segment is pivotally secured to the sleeve base 85 at one end by means of the screw 95, the other end terminating in a cam roller 96. The spring 101, held by the screw, serves to urge the inner edge of the arm 94 into contact with the sleeve 82, a suitable slot 97 (Fig. 6) being provided in said sleeve for the reception of the roller 96. An elongated fixed cam 98 in the form of a narrow plate is supported by the frame of the machine with its faces vertical and serves to operate the arm 94 and therethrough to operate the sleeve 82 and the arms 74 and 78 to rotate the gripper 57 about the post 83 at the proper time. That is, in the position of the gripper 57 shown in Fig. 4, the roller 96 is in the cut-away portion 99 of the bottom edge of the cam 98 and the gripper arm 74 extends at substantially right angles to the cam 98. As the gripper moves toward the right from the position of Fig. 4, and turns the glove, the cam roller strikes the bevelled edge 100 and is moved thereby in a counter clockwise direction as viewed in Fig. 4 against the action of the spring 101 and into the dash-dot line position shown at the right of Fig. 4 away from the sleeve 82 thereby causing no rotation of the gripper about the post 83. The cam roller continues to ride on the cam 98 until it reaches the bevelled

portion 102 where it drops off the cam into the cut-away lower edge 103 thereof, the arm 94 returning to its initial position with its inner edge against the sleeve 82 under the action of the spring 101. After the gripper has been operated to release the jaws and begins its return movement back toward the left, the glove having been completely turned and mounted on the form 10 at this time, the cam roller 96 strikes the bevelled portion 102 and as the gripper continues its return movement toward the left, said roller causes the arm 94 together with the sleeve 82 and the gripper part carried thereby to rotate about the post 83 in a clockwise direction as viewed in plan and into the position shown in Fig. 5. In this position, the gripper is out of the way of the horizontal form 10 which may now move upwardly, the uppermost form 12 at the same time moving downwardly, as shown by the respective arrows of Fig. 1.

So long as the roller 96 remains on the cam 98 during the movement of the gripper toward the left, said gripper remains in its turned position as shown in Fig. 5. Movement of the grippers toward the left gives the lowermost form 10 sufficient time to be moved into the glove receiving position thereof without interfering with said lower gripper. On the continued movement of the grippers toward the left, the cam roller 96 moves off the cam 98 into the cut-away portion 99 thereof whereby the spring 84 becomes operative to rotate the sleeve 82 and the parts carried thereby into the normal positions thereof shown in Fig. 4 ready for the repetition of the operation.

Means may be provided for assisting the grippers 57, 58 to mount the glove on the heating form 10. Such means is preferably used where a cheap variety of glove is operated upon or the material of the glove is unusually weak and likely to tear under the pull of the grippers required to mount the glove on the heating form, or where the material of the glove is so resistant to deformation that substantial resistance is offered to the mounting operation. In cheap gloves particularly such as those made of canvas, the stitching is frequently inaccurate so that the glove fingers are stretched to a varying extent to mount the turned glove on the heating form. Additional mounting blades designed to enter between the fingers of the gloves and press upon the bottoms of the fingers to assist the grippers to mount the glove, are therefore advisable.

As shown in Figs. 1 and 10, a set of three finger draw-on blades 104, 105 and 106 are each arranged to oscillate between a different pair of the fingers of the heating form 10 near the end part of the mounting stroke of the grippers 57, 58. Said blades are each comparatively thin and wide and are mounted on the vertical oscillatory shaft 107 to move into the respective spaces between the fingers of the heating form and thereby to draw the glove fingers on to the fingers of the heating form assisted by the pull of the grippers on the wrist part of the glove.

To oscillate the shaft 107 and the draw-on fingers, a bevel gear 108 on said shaft engages the bevel gear 109 on the horizontal shaft 110, which carries the crank 111. One end of the link 112 is secured to the end of the crank 111, and the other end secured to the crank arm 113 loosely pivoted on the shaft 11 and having a cam roller 114 in engagement with the cam 115. To maintain said cam roller and cam in contact, a spring 116 connected to a fixed part of the

frame and to the crank 111 is provided. The cam 115 is mounted on the shaft 117 which is arranged with respect to the shaft 11 similarly to the arrangement of the shaft 18 with respect to the shaft 15. The shaft 117 being driven in the same manner as the shaft 18 as hereinbefore explained in connection with the description of the shaft 18, the explanation need not be repeated.

Rotation of said shaft 117 causes continuous rotation of the cam 115 thereby oscillating the crank arm 113 and through the link 112 oscillating the crank 111 and the bevel gear 109. The vertical blade-carrying shaft and the draw-on blades carried thereby are oscillated through the bevel gear 108 to cause the blades to assist in mounting the glove fingers on the form in the manner hereinbefore described.

It will thus be seen that I have provided a form designed particularly to retard movement of the finger tips of the glove off the form during the glove turning operation and particularly to retain full control of the glove thumb, that the glove turning mechanism is comparatively simple but efficient and that I have provided a mechanism well designed to meet the perplexing problems occurring in practical operation of a glove turning machine.

While I have shown and described a certain specific embodiment of my invention, I do not wish to be understood as limiting myself thereto but intend to claim my invention as broadly as may be permitted by the state of the prior art and the scope of the appended claims.

I claim:

1. In a glove turning machine, a turning form including a thumb member comprising a pair of spring plates arranged to enter the thumb of a glove mounted on the form, a heating form, means for intermittently rotating said forms to carry said forms into an aligned position while said forms are at rest, and an oscillatory tucker blade swingable between said plates to tuck the tip of the glove thumb from a position outside of said plates to a position between said plates while said forms are at rest, a glove gripper including a pair of spring pressed jaws, means for reciprocating said gripper longitudinally of the forms through a stroke extending from the inner end of one of the forms to the inner end of the other form, means for opening the jaws at each end of the stroke and for closing said jaws during the intermediate part of the stroke, and means for rotating one of said grippers out of the path of said forms when said forms are rotated out of the rest positions thereof.

2. In a glove turning machine, a movable turning form including finger tubes and a thumb member consisting of a pair of spring plates, a movable heating form, means carried by the heating form for tucking the finger tips of a glove into the finger tubes of the turning form while the forms are at rest, separate means for tucking the tip of the glove thumb in between the plates of the thumb member while the forms are at rest, a pair of relatively movable glove gripping jaws and means for closing said jaws upon opposite faces of a glove on the turning form and for then moving the jaws lengthwise substantially throughout the lengths of the turning and heating forms to turn the glove and to mount the glove on the heating form while the forms remain at rest.

3. In a glove turning machine, an intermit-

tently rotatable turning form, an intermittently rotatable heating form, and means for turning a glove mounted on the turning form and for mounting said glove on the heating form comprising a pair of jaws, one of said jaws being spring pressed toward the other jaw, said other jaw being of resilient compressible material, means for reciprocating said jaws from a point adjacent the inner end of one form to a point adjacent the inner end of the other form while said forms are at rest, and means for arranging the jaws at opposite faces of a glove on the turning form and for opening said jaws at the beginning and end of the stroke and for closing said jaws during the intermediate part of the stroke and while said forms remain at rest.

4. In a glove turning machine, a turning form having four fingers and a thumb member, said thumb member comprising a pair of spring plates, means for supporting said plates at the inner ends thereof, the outer free end portions of said plates being normally in contact, a heating form and means for turning the fingers and thumb of a glove mounted in inside-out position on the turning form and for mounting the glove on the heating form, said means comprising rods carried by the heating form and slidably beyond said heating form and into the fingers of the turning form to tuck the finger tips of the glove into the fingers of the turning form, a tucker blade mounted independently of said forms and movable while said forms are at rest between said spring plates and away from said spring plates to tuck the tip of the glove thumb between said plates, glove gripping jaws, and means to operate said jaws to grip therebetween the inner end of a glove mounted on the turning form and to move said end to the inner end of the heating form.

5. In a glove turning machine, an intermittently rotatable heating form, rods slidably in and beyond said form, a hollow turning form adapted to have a glove mounted thereon in inside-out position, said turning form including a pair of spring plates arranged to enter the glove thumb, a tucker blade, means for oscillating said blade to tuck the tip of the glove thumb between said plates and then to recede from said plates while the forms are at rest, a pair of glove gripping jaws and means to close said jaws upon opposite faces of the open end of a glove on the turning form and then to move said jaws and said open end to the inner end of the heating form and then to release said jaws from said open end.

6. In a glove turning machine, a plurality of heating forms intermittently rotatable about a common axis, a plurality of turning forms intermittently rotatable about a common axis, each of said turning forms having four tubular fingers open and outwardly flared at their free ends and having a pair of spring plates adapted to enter the glove thumb, means carried by the heating forms to tuck the finger tips of a glove into the fingers of the turning form when the heating form is aligned with the turning form, means mounted independently of and movable independently of the forms and between said plates to tuck the tip of the glove thumb between said plates while the forms are at rest, a continuously movable chain, a pair of glove turning jaws, and means including a slide operatively connecting the jaws to the chain to reciprocate the jaws from the wrist part of one form to the wrist part of the other form while said forms are at rest.

7. In a glove turning machine, an intermittently rotatable form having a wrist portion, means for gripping, at the wrist portion, the open end of a glove mounted in inside-out position on the form and for carrying said end longitudinally of the form, said gripping means comprising a fixed jaw, a spring pressed movable jaw, means including a cam for moving the movable jaw toward the fixed jaw to close the jaws on opposite faces of the glove, and means for rotating said jaws as a unit out of the path of the form when said form is rotated.

8. In a glove turning machine, means for gripping and turning a glove comprising a pair of glove gripping members, each of said members comprising a fixed jaw and a movable jaw, and means for opening and closing said jaws upon opposite faces of a glove and for also reciprocating said jaws as a unit, said last mentioned means including a cam lever connected to the movable jaw, a fixed cam for operating said lever, a slide carrying said lever and a continuously traveling chain connected to said slide.

9. In a glove turning machine, a form provided with tubular fingers, one of said fingers being open along one side at a part adjacent the inner end thereof and means for gripping the open end edge of a glove mounted in inside-out position on said form with said edge arranged at the open side of said finger, said means comprising a pair of jaws, one of said jaws being arranged normally outside of said finger and means for moving the other jaw into a position first inside of the open end of said finger and then toward the other jaw, and means for reciprocating said jaws as a unit.

10. In a glove turning machine, a pair of spaced forms movable into and out of an aligned position thereof, and means for removing the glove from one form and turning and mounting the glove on the other form while the forms are at rest comprising finger and thumb tucking members, longitudinally movable grippers to grip the wrist part of a glove on one form and to move said part to the other form, and finger draw-on blades movable into and out of the spaces between the fingers of said other form.

11. In a glove turning machine, a form having spaced fingers, means for turning a glove and for mounting the fingers of the glove on the fingers of the form, a series of draw-on blades movable into and out of the spaces between the fingers of the glove and of the form, and means for moving said blades into said spaces after the fingers of the glove have been drawn partway on to the fingers of the form to complete the mounting of the glove fingers on to the form fingers.

12. In a glove turning machine, a form having a tubular finger open at an end thereof and for a portion of one side adjacent said end, and a pair of reciprocating jaws movable through the open side of the finger into a position wherein one jaw is on one side of a glove mounted on the form and the other jaw is on the other side of said glove.

13. In a glove turning machine, a form having a tubular finger open at an end thereof and for a portion of one side adjacent said end, a pair of reciprocating jaws movable through the open side of the finger into a position wherein one jaw is on one side of a glove mounted on the form and the other jaw is on the other side of said glove, and means for opening the jaws at the ends of the reciprocating stroke thereof and for

closing the jaws during the intermediate part of said stroke.

14. In a glove turning machine, a form having a tubular finger open at an end thereof and for a portion of one side adjacent said end, a pair of reciprocating jaws movable through a glove turning stroke and a return stroke, means for moving the jaws through the open side of the finger into a position wherein one jaw is at the outer surface of a glove mounted on the form and the other jaw is at the inner surface of said glove, means for opening the jaws at the ends of the reciprocating stroke thereof and for closing the jaws during the intermediate part of said stroke, and means for turning said jaws as a unit during the return stroke thereof.

15. In a glove turning machine, an intermittently rotatable heating form, rods slideable in and beyond said form, an intermittently rotatable turning form adapted to have a glove mounted thereon in inside-out position, said turning form including tubular fingers arranged to receive the ends of said rods when the forms are at rest to tuck the glove finger tips into the tubular fingers, and a pair of spring plates arranged to enter the glove thumb, a tucker blade of greater width than its thickness, and means to operate the blade while the forms are at rest first to force the edge of the blade between the plates and thereby to forcibly tuck the glove thumb between the plates and then to retract the blade.

16. In a glove turning machine, an intermittently rotatable heating form, rods slideable in and beyond said form, an intermittently rotatable turning form adapted to have a glove mounted thereon in inside-out position, said turning form including tubular fingers arranged to receive the ends of said rods when the forms are at rest to tuck the glove finger tips into the tubular fingers, and a pair of spring plates arranged to enter the glove thumb, a tucker blade of greater width than its thickness, means to operate the blade while the forms are at rest first to force the edge of the blade between the plates and thereby to forcibly tuck the glove thumb between the plates and then to retract the blade, and means for gripping opposite faces of the open end part of the glove and to move said end part longitudinally of the forms while the forms are at rest.

17. In a glove turning machine, an intermittently rotatable heating form, an intermittently rotatable turning form including a pair of spring plates constituting a thumb member, means for moving the forms into an end to end aligned position, means carried by and projectable from the heating form to tuck in the finger tips of a glove mounted on the turning form while the forms are at rest, and means mounted independently of the forms and movable independently of the forms while the forms are at rest for tucking in the thumb of the glove between said plates.

18. In a glove turning machine, an intermittently rotatable heating form, an intermittently rotatable turning form including a pair of spring plates constituting a thumb member, means for moving the forms into an end to end aligned position, means carried by and projectable from the heating form to tuck in the finger tips of a glove mounted on the turning form while the forms are at rest, and means mounted independently of the forms and movable independently of the forms while the forms are at rest for tucking in the thumb of the glove between said plates, said last mentioned means comprising

ing a tucker blade of greater width than its thickness, and means for alternately moving the end edge of the blade in a substantially straight line path between the plates and retracting the blade away from the plates.

19. In a glove turning machine, a pair of relatively movable glove gripping jaws, means for reciprocating said jaws as a unit in a horizontal straight line path while opening and closing the jaws, and means for turning said jaws as a unit about a vertical axis spaced from the jaws during the reciprocation thereof.

20. In a glove turning machine, a glove form on which an unturned glove is manually mountable, said form including tubular fingers outwardly flared at the free ends thereof, and a thumb member arranged to enter the thumb of the glove, said thumb member comprising a pair of similar plates arranged in face to face relation and spaced apart throughout the greater part of the lengths thereof and having intermediate bowed portions outwardly convex to provide an enlarged space between the plates, said plates having free end portions in contact with each other.

21. In a glove turning machine, an intermittently rotatable turning form, an intermittently rotatable heating form, and means for turning a glove mounted on the turning form and for mounting said glove on the heating form comprising a pair of jaws, means for reciprocating said jaws from a point adjacent the inner end of one form to a point adjacent the inner end of the other form while said forms are at rest, and means for arranging the jaws at opposite faces of a glove on the turning form and for opening and closing said jaws.

22. In a glove turning machine, a movable turning form including finger tubes and including a thumb member consisting of a pair of bent spring plates, a movable heating form, means for tucking the finger tips of a glove into the finger tubes of the turning form while the forms are at rest and for tucking the tip of the glove thumb in between the plates of the thumb member, a pair of relatively movable glove gripping jaws, and means for closing said jaws upon opposite faces of a glove on the turning form and for them moving the jaws lengthwise to turn the glove and to mount the glove on the heating form while the forms are at rest.

23. In a glove turning machine, an intermittently rotatable heating form, a hollow turning form adapted to have a glove mounted thereon in inside-out position, said turning form including a pair of bent spring plates arranged to enter the glove thumb, a tucker blade of greater width than thickness, means for moving said blade to tuck the tip of a glove thumb between said plates while the forms are at rest, a pair of glove gripping jaws, and means to close said jaws upon opposite faces of the open end of a glove on the turning form and then to move said jaws as a unit.

24. In a glove turning machine, a plurality of heating forms intermittently rotatable about a

common axis, a plurality of turning forms intermittently rotatable about a common axis, each of said turning forms having four tubular fingers and having a pair of spring plates, said fingers being adapted to enter the fingers of a glove and the plates being adapted to enter the glove thumb, means to tuck the finger tips of a glove into the fingers of the turning form and to tuck the glove tip between said plates when

5 the heating form is aligned with the turning form, a chain, a pair of glove turning jaws, and means including a slide operatively connecting the jaws to the chain to reciprocate the jaws on operation of the chain and while said forms are at rest.

25. In a glove turning machine, means for gripping and turning a glove comprising a pair of glove gripping members, each of said members comprising a pair of jaws, and means for opening and closing said jaws upon opposite faces of a glove and for also reciprocating said jaws as a unit, said last-mentioned means including a fixed cam, means operatively connecting the cam to the jaws, a slide carrying said connecting means, and a chain connected to the slide.

26. In a glove turning machine, a glove form on which an unturned glove is manually mountable, said form including tubular fingers and a thumb member arranged respectively to enter the fingers and thumb of the glove, said thumb member comprising a pair of similar plates arranged in face to face relation and spaced apart throughout the greater part of the lengths thereof, and having free end portions in contact with each other, said form having a longitudinal groove at the wrist end thereof, a tucker blade to tuck the tip of the glove thumb between said plates, means for operating said blade, gripper means adapted to enter the groove of the form to grip opposite faces of the glove thereon, and means for reciprocating the gripper means.

27. In a glove turning machine, a form having a tubular finger open at an end thereof, said form having a longitudinal groove in the wrist end thereof, a gripper movable into said groove and into a position wherein it is arranged on the inside of the glove mounted on the form, a relatively fixed gripper on the other side of the glove cooperating with the first mentioned gripper to grip a glove therebetween, means for reciprocating the grippers as a unit, and means for moving the first mentioned gripper toward and from the other gripper.

28. In a glove turning machine, a form having a tubular finger open at an end thereof, said form having a longitudinally arranged groove therein adjacent the other end thereof and a pair of reciprocatory jaws, at least one of said jaws being movable into said groove and into a position wherein said one jaw is on one side of a glove mounted on the form, the other jaw being movable into a position on the other side of said glove on the reciprocation of said jaws.
